DESIGN FOR A STOKER

Frederick W. Vodoz, Wilmette, Ill., and Alfred H. Haberstump, Detroit, Mich., assignors to The Murray Corporation of America, Detroit, Mich., a corporation of Delaware

Application October 22, 1938, Serial No. 80,630

Term of patent 14 years

To all whom it may concern:

Be it known that we, Frederick W. Vodoz and Alfred H. Haberstump, both citizens of the United States of America, residing in Wilmette, in the county of Cook and State of Illinois, and Detroit, in the county of Wayne and State of Michigan, respectively, have invented a new, original, and ornamental Design for a Stoker, of which the following is a specification, reference being had to the accompanying drawing, forming a part thereof, wherein:

Figure 1 is a side view in perspective of a stoker embodying our new design;

Figure 2 is a perspective view of the stoker illustrated in Figure 1, taken from the rear;

Figure 3 is a perspective view of the stoker illustrated in Figures 1 and 2, taken from the front; and,

Figure 4 is a perspective view of the stoker illustrated in Figure 1, taken from the opposite side thereof.

We claim:

The ornamental design for a stoker, substantially as shown.

FREDERICK W. VODOZ.
ALFRED H. HABERSTUMP.
